(57) **CLAIM**

The ornamental design for a weatherproof cover for electrical device, as shown and described.

DESCRIPTION

FIG. 1 is a front perspective view of a weatherproof cover for electrical device showing our new design;
FIG. 2 is a rear perspective view thereof;
FIG. 3 is a top plan view thereof;
FIG. 4 is a right side view thereof;
FIG. 5 is a left side view thereof;
FIG. 6 is a front view thereof;
FIG. 7 is a rear view thereof;
FIG. 8 is a bottom plan view thereof;
FIG. 9 is a bottom perspective view thereof; and,
FIG. 10 is a perspective view thereof, with the cover shown in a partially open position.
The broken lines shown represent unclaimed subject matter and form no part of the claimed design.
